(57) **CLAIM**

I claim the ornamental design for a spanner, substantially as shown and described.

DESCRIPTION

FIG. 1 is a top, perspective view of the spanner; the view showing my new design;

FIG. 2 is a front elevation view thereof;

FIG. 3 is a rear elevation view thereof;

FIG. 4 is a side elevation view thereof;

FIG. 5 is a side elevation view thereof;

FIG. 6 is a top view thereof;

FIG. 7 is a bottom view thereof;

FIG. 8 is a bottom, perspective thereof; and,

FIG. 9 is a top, perspective view thereof; the view showing the spanner in exploded format.

A description of the appearance of the article is as follows:
A spanner.

The broken lines are for the purpose of illustrating environmental structure and portions of the spanner that form no part of the claimed design.
